(76) Inventor: **John M. McClintic**

John McClinic

Letters Patent Patented Oct. 8th 1827

Assigned Oct. 27. 1835 }
The Schedule referred to in these Letters Patent and making part of the
same containing a description in the words of the said John McClinic
himself of his improvement in the machine for mortising and tenoning
Timber, for which Letters Patent were granted dated the eighth day of October
1827, which Letters Patent being hereby canceled on account of a defective
specification.

To all to whom these Presents shall come

Be it known that I John McClinic of Chambersburg in the County of Franklin and State of Pennsylvania have invented a new and useful improvement in the machine for mortising and tenoning timber. That my first Patent has been canceled by me in consequence of a defective specification and not with fraudulent intent.

The following is a full and exact description thereof; 1st. There is a frame made say two feet four inches high and three feet long & two feet wide this being sufficiently large for ordinary mortising & tenoning viz. Doors, Shutters, Sash, Venetian Blinds, Bedsteads, Bureau & Table legs &c. but if intended for heavier work will of course be increased in size. The stuff of which the above frame or buck is made is of oak or other hard wood, scantling about five inches by four squared. On this frame is erected two stiles or upright posts of hard wood of about two & half inches thick & eight or nine inches wide mortised through both sides and double keyed below. These posts stand above the frame from three to four feet according to the kind of work the machine is intended for.

There is a top rail framed from post to post & keyed above. These posts are squared or planed in center of inner sides about one fourth of an inch in depth and two inches wide for the chisel carriage to slide up and down in instead of upright posts being made of plank eight or nine inches wide as spoken of they may be framed and the parts which are planed, squared to the rails connecting the side pieces of the posts.

2d. There is a chisel carriage framed of hard wood of the breadth of the

machine, between the rabbits or grooves of upright posts and about two feet in length, with five rails viz, two side rail (which are those that slide in grooves of upright posts) a top rail a bottom and middle rail. The bottom rail is from the top to four inches thick & three inches wide, with a slip mortise across it in centre with an iron plate above and below. Up through this mortise the long or shank of the chisel or chisels are put and fastened on upper side of rail by nut that screws on chisel shank. The middle rail of this carriage is about three and a half inches wide tenoned into top and bottom rail; where it is tenoned into bottom rail, it is double tenoned, straddling the place or mortise where chisel is fastened and is cut away about four inches up between the tenons so as to admit a nut to tighten the chisels. 3d. There is a rail framed through sides of bench flush below & as high as grooves in bench pieces where the table slides about two and half inches thick up through the rail from the lower side is put two eye bolts distant from each other the breadth of whatever your middle rail of chisel carriage is, and stand below the rail about three inches between these eye bolts hangs a lever fastened by an iron pin passing through the eye bolts and eye plates that are riveted to sides of lever with a nut screwed on pin up against the eye bolt.

4th. From near the top of middle rail of chisel carriage to the heel of lever there are two straps of iron about an inch & quarter wide and an eighth thick and about three feet long fastened in each place by an iron pin and riveted close to sides of middle rail and plates are lever. These straps are the movers of the chisel carriage, as you raise the lever the carriage rises as you press down lever, chisel is forced into the wood.

5th. There is a sliding table, which slides between bench sides which are grooved within about $\frac{1}{2}$ of an inch of upper edge. This table is moved in and out by means of a tail screw which passes through a rail that is framed thru' bench sides same as everywhere the lever hangs. This table brings your piece to the proper place to be mortised or tenoned. On this table there are two guide pieces, the one permanently fixed, the other movable, so that when you put in your piece to work upon, it is placed against the fast guide the moving guide is then placed against the piece and then tightened, which is done by means of two screws that pass

tho' loop holes in sliding guide and not in table. Instead of suoring your piece between the guides spoken of above, there is a box of about two & a half feet long five or six inches in depth and about four inches wide, the sides of this box are grooved near the lower edge, and in these grooves, tongues that are on the guide pieces (spoken of) work allowing the box to slide fair thro' the machine, also preventing the box from raising as the chisel is raised out of cut.

6th. The two upright posts have each a large opening in them according to the breadth or height wished. The lower edge of these openings are flush with top of moving table. Thro' those openings your piece to be mortised or tenoned may which is fed to the chisel by hand that is not engaged with the lever. When the box is used the stuff is held in box by a screw through side of box pressing the piece against the other side of box. The box is then passed thro' the machine by a rack and pinion wheel, the rack is screwed to side of box, above the groove on the table there is a short stud erected thro' this stud, a handle passes, and on the end a pinion wheel about an inch & quarter in diameter which goes into rack on side of box. As you turn this handle, your box slides thro' the machine and with it your piece, which is held firm in box. There are two stirrups of iron that come over the sides of the box, that may be shifted to whatever breadth of stuff you are working on and tightened by screws these stirrups or pieces prevent your piece from raising in box as the chisel is raised out of cut. To commence a mortise for instance on a door slat of hard wood which is to be mortised thro', you bore two holes (soft wood not necessary to bore) of the breadth of your mortise, half the depth of your slat, viz. one on each side of your piece at the recessed ends of mortise, commenced at one hole & mortise half the depth of your piece and as far as your heading scribe, then turn your piece end for end keeping the same side to you and mortise the other half. When your piece is taken out, you can with a core driver knock out all the chips. If you wish to mortise thro' from one side you will then bore one hole thro' your piece, & the depth you want, if not through.

7th. For tenoning, if there be a shoulder wanted on both sides of tenon, you place two chisels in your machine as far apart as the thickness you want your tenon or one chisel if made in one piece, described hereafter. In cutting down your tenon

you will take out of about one fourth of an inch, leaving about one fourth of an inch stand before you come to shoulder, which quarter is removed by a former chisel by the shoulder is sawed down, which is not done until tenon is cut. When you cutting tenons or mortising thro' from one side you will have a piece of stuff filled to inside of box for chisel to cut against, that your bar may not be injured, this piece is screwed down in box. For the greater ease of moving the stile from mortise to mortise (where they are long and heavy) there is a piece of stuff about half an inch or three quarters thick filled to breadth of box inside and screwed down in set (screws countersunk) projecting beyond the box at each end some two or three feet or what may be thought necessary. For bevel mortising there is a false bottom filled to breadth of box inside counterbated at end and a pin of iron run through sides of box and false bottom, this bottom is raised at the loose end to whatever splay wanted, is kept at that pitch by wedge between the two bottoms or screws up through lower bottom or otherwise. This bottom may be taken out when not mortising bevel work which will increase the depth of your box if wanted.

8th. The chisels used in this machine are similar to the common mortising chisels with the difference that the longer shanks are square and a saw cut on long to fasten them in bottom of each of chisel carriage. There are also other chisels used in the machine, viz... 1 chisel for mortising for the slots of Venetian shutters, this chisel is composed of a socket made with an oblong hole in it to receive the chisel, which is two half bills of whatever size wanted and fastened in socket by two screws running thro' side of socket against the bills and pressing them tight together against the other side of socket. This socket has a round long so that it may be turned in machine to suit right or left stiles. Also a square four sided chisel which is intended for saws, viz... the usual square mortising cross, mauls & meeting rails, for this kind of chisel there is a hole bored within the square of the mortise the chisel then cuts down the four sides the block or chip sticking in the chisel is forced out of it by a crooked tool entering the chisel above the block. There is also used in machine what I call double & triple cutting chisels; which chisels are used (principally) when working on stuff in which the core packs rather tight; Also used at times when the mortising does not go through. One of these chisels is similar to the

comes out of first chisel spoken of with this difference that on the back part of it, it is peballed down about half the breadth & half the thickness of chisel, which forms two cuts, the thick chisel as I shall call it standing about one fourth of an inch below the short one (when in the pin achieved) as this chisel is faced into the wood, the chip which is cut by the short part is held on one side by the side of the long chisel and on the other side by the standing part of the piece being mortised which forms a case for the chip, and is bro'd out as the chisel is raised out of cut. The stub cutting pretty much like the last described with this difference it is peballed down in middle making as it were three chisels, the two outside ones being about a quarter of an inches longer than the middle one; In this chisel the chip of the short chisel is bro'd up between the two long chisels. In forming the box or peballed part in this last chisel you will make it a little wider as you go upwards so that the chip will forced out easily by the succeeding chip if any has stuck in also a double faced chisel which is as if you would place two chisels together back to back, this chisel also is used for pack stuff as heretofore described. The two are bolted together by screw bolts passing through both or there may be socket similar to the Venetian chisel socket so that different sizes may be used in it.

Mortising and tenoning may be done in many ways to joint the gate or part which holds the chisel or chisels may be worked by Rack & Pinion wheel or crank & balance wheel or beadle & spring to raise the gate or part which holds the chisel.

Description of Machine.

When the pack & pinion snaker is used it is made of wood is very similar to the make of that already described in many or most of its parts with this difference that the upright parts or studs are not more than seven inches wide except at that part where the box (which holds the stuff) passes through. Neither need the machine be made as wide between the studs. The bench may be framed about one foot four inches out. The upright posts if made of wood mortised into bench sides and as before keyed below but if of casting may be bolted to top of bench sides which may also be made of casting together with table, &c. The upright posts or studs have mortises made in them or loop holes through which the tines of two rails connecting the studs and are keyed or pulled against the outside of studs. These loop holes are for the purpose of changing the height of

rails when necessary, the rails should fair on sides of studs have each a hole through in about an inch and half in diameter. The Rack which is that part which holds the chisel is of steel is about one foot twelve inches long and about one and one fourth inches in diameter with its thickest part, which is from the center each way about four inches making eight inches. This part is turned into grooves about a quarter of an inch deep, which forms coggs around the shaft. The other parts of chisel back are turned down to a little more than an inch in diameter which is seven inches at each end of Rack. These plain parts pass through the holes in rails described above, when the pinion wheel is worked. There are two plates of metal drilled precisely to fit the plain parts of rack and are bolted to tops of rails when the rack is plumb. These plates may be about half inch thick. There is a spur wheel of seven inches in diameter (this being the most useful size) and an inch thick, cogged out fine and grooved in the chisel back. The shaft on which the wheel is fastened is turned with a flange or shoulder on it that the wheel may be fastened to and kept from turning on the shaft. The bearing of the shaft are fastened to the sides and edges of upright studs and are so constructed as to be moveable or out up or down, so as to gear to proper pitch or if mounted a different sized wheel. The pinion wheel which is seven inches in diameter being turned one fourth around gives to chisel back a perpendicular motion of five and a half inches which is considerably more than is generally provided when you mortise on both sides of piece. If you wish to mortise say through a slit of eight inches from one side, you can place on your shaft a wheel of ten inches diameter. This with a little more motion of wheel will carry you the eight inches deep. In and through the pinion wheel near the outer edge, there are holes drilled on the same circle through which there is a small screw bolt put which fastens your handle against side of pinion. Your handle is a bar of iron about three and half feet long, two inches wide where it is fastened to wheel and tapered towards ends to about an inch the bar about three eights or half inch thick, hole drilled thru filling the shaft with small holes sailing the hole in wheel so as to change pitch. At the end next the wheel it will extend a little beyond the wheel have a hole drilled through for the purpose of attaching a weight or spring that

the Rack may stand when lifted. The chisel used in this machine are the same as those already described with this difference that the longer shanks are all ground and fit into chisel crack, which is bored in each end of each end about three inches in depth, the holes about half inch in diameter and a little tapered with holes bored therin for the purpose of knocking out tool.

The lower part of rack which moves in lower rail is flattened on two opposite sides to about one sixth of its diameter on each square. The use of these holes in the other end of Rack is for the purpose of fastening a spring to raise the rack if the machine is worked by the foot, or that if the rack is placed horizontally that there may be a chisel in each end and working on two slides, in which case the lever will be double length extended either beyond the wheel, that they are assisting each other. The flat parts of rack, are for the purpose of changing the direction of the face of the chisel by turning the rack around. There is a spring fastened to top or bottom of the rail, which spring lays fair against the square part without pressing it hard, which spring gives out as you wish to turn the rack around.

The sliding table of the machine where the rack and pinion make is used, differs a little from the other make in this that the little stand which has the small wheel on which moves the box the machine is erected on the table on the side next the tail screw; also the screw which tightens the piece in box, all being at the end you are working at. In the other make the tail screw is at opposite end from where the lever is fixed; instead of moving the box through the machine with rack & pinion by hand, there may be a feeding part attached that will feed it self, when machine is worked, this may be done in many ways for instance the rack and pinion may be worked similar to saw mill, or it may be done by rollers or the piece or the part that it is fastened to may be shoved by screw or end less screw; also the holes which are necessary to be bored for mortising hard wood, or using any particular chisel may be done by attaching a boring machine, but the more you add, the more likely to be out of repair. For if the machine fed itself must do it at some uniform stroke, say eighths or quarters of inches, it would sometimes fall short or go beyond the heading scribe, whereas if it worked by the rack and pinion or any other way by hand you can take much or little

hand, according to the stuff you working on. The aforesaid machinery may be worked by water, steam, horse, hand, or any other power that may answer by adding the necessary gear. That described being used by hand.

Operation of Rack & Pinion. Machine.

When you place your piece in the box, and tighten it thereby the screw through side of box, your sliding table on which the box rests, is moved in or out, bringing the piece in box to the proper place to be acted on; you then let your chisel, which is in the rack rest on top of piece; give your lever what ever inclination you choose by changing the thumb screw pin (which passes through wheel & lever) into a different hole on wheel higher or lower as you may want it. If the mortise is to be deep, it will be best to set the lever about one eighth of the circle of the wheel above level. This when you have pressed your lever or handle to one eighth of the circle below level, will give one fourth of wheel or five and half inches deep.

Where the machine is operated on by the foot, it will be necessary to affix a treadle connected with the part which holds the chisel or with the upper end of handle; Further it will be necessary where foot is used for forcing the chisel into the wood that there be a spring or weight sufficiently strong or heavy to raise the gate or part which holds the chisel out of the cut, when the pressure of the foot is taken off the treadle. If spring is used it may be of wood, steel or iron or anything else of sufficient strength and elasticity and may be attached to frame of machine, in such a way as to lift the part which holds the chisel. In the rack & pinion machine the spring may be a spiral spring made of strong wire, and may be attached to top of chisel rack or set below the wheel operating on the rack, in this case the wheel is pulled downward in such way that the rack is forced upward, besides spring there may be a weight attached to wheel or to the end of handle next to wheel which weight is a little heavier than the chisel rack, this weight being necessary to balance the rack, that it may stand in any position, where the hand is used instead of the foot. Instead of applying springs or weight for the purpose of raising chisel out of cut or cut, they may be applied so as to force it into cut in many ways one of which may be in this way viz. By hanging a weight to lever as far

out on it as will force the chisel to cut & to be raised out of cutting crank of a wheel, or by a person on a shaft that may be so shifted as to raise the chisel up higher than is necessary; besides the chisels that are particularized. Chisels of any shape or form may be used in the machine. There may be a rack used separated from the part holding the chisel the rack in which case would be stationary, that is, it would not turn around the socket or part holding the chisel having but one motion, that is that of turning round changing the face of chisel or the direction of it but not sliding up and down as in other described. That motion will be in sides of upright posts. The rack turned on shaft is preferable because bringing your pressure more directly above the chisel.

What I claim as my own invention and not previously known in the above described machine is the manner in which the parts which hold the chisels are constructed. Also the manner in which they are worked viz. The strips connecting the chisel carriage and lever the holes in lower parts of strips for changing to different breadths of stuff and keep the lever as horizontal as will give you the necessary depth.

Also, the Rack & Pinion, viz. the chisel rack & wheel which works it, the manner & make of, and mode of operating, viz. the turning the rack round, bringing the face of the chisel, in opposite direction for heading down; Also the sliding table bringing the piece which is in the box to the quarrying or proper place to be worked on; Also the box which holds the stuff & the manner of moving it; Also the round long on chisel; Also the make of socket for Venetian shutter chisel & bills; Also my four sided chisel; Also my double cutting chisel; Also my triple cutting chisel; Also the two faced chisel; Also in operating by treadle and spring.
